UNITED STATES PATENT OFFICE.

EDWARD REICHENBACH, OF ORRVILLE, OHIO.

DITCHING-LEVEL.

SPECIFICATION forming part of Letters Patent No. 341,690, dated May 11, 1886.

Application filed October 30, 1885. Serial No. 181,355. (No model.)

To all whom it may concern:

Be it known that I, EDWARD REICHENBACH, a citizen of the United States, residing at Orrville, in the county of Wayne and State of Ohio, have invented certain new and useful Improvements in Ditching-Levels, of which the following is a specification.

My invention relates to a new and useful level for employment in making ditches for 10 draining land and other similar purposes.

The invention consists of certain novel parts, combinations of parts, and features of construction, first hereinafter described, and then designated in the claims.

15 The invention is illustrated in the accompanying two sheets of drawings, in which Figure 1 is an isometric view of the level mounted on the extension-standard. Fig. 2 shows two views of the front or "eye-piece" end of the level. Fig. 3 shows two views of the opposite or target end of the level. Fig. 4 is an isometric view of the target. Fig. 5 is a rear side view of the target. Fig. 6 is a side view of the level mounted on a straight-edge drag-bar.

25 Fig. 7 is an end view of same. Fig. 8 is a view illustrating the manner of using the level when sighting the target and calculating distances.

The body A of the level has at each end a boss, B C, which is elevated or projects above 30 the top surface of the body, and each boss has a horizontal bore, *a*, which constitutes the "sights," one in line with the other. The bore in boss designated by B is the eye-piece bore, and the end *b* of this bore, to which the 35 eye is applied, is open, while the opposite end is covered with a plate, *c*, having three sight-holes, *c'*, arranged in a vertical line one above the other. The middle one of these three holes is designed to be in sight-line with the horizontal wire *d* and target, hereinafter mentioned, when the body A is level. The bore in the boss C at the other end has a cross consisting 40 of two wires, *d*, placed at right angles. One wire extends horizontally and one vertically.

45 This latter has position only below the horizontal wire. If desired, a lens may be attached in one or both of the horizontal bores *a* of the sights. Without the lenses, however, the device answers a useful purpose.

50 To insure that the instrument will be adapted for estimating or measuring distances in do-

ing the work for which it is intended, the space between the three holes *c'* at the eye-piece must be proportioned to the space between the two sights—that is, the hole-plate *c* and the wires *d*. This proportion may be found either by experiment or by mathematical calculation. One way, for instance, of finding this proportion, is as follows: If the space between the two sights be thirty-four inches, and the triangle which is formed by the diverging sight-lines *d'* when sighting through the middle hole and the upper or lower hole, as denoted in Fig. 8, widens at the rate of one inch per rod, and the target be one rod from eye-piece, then 55 the triangle thus formed will be one rod long, less thirty-four inches—the space between the two sights—and one inch high, and in this case the space between the upper and lower holes in the plate at the eyesight-bore will be seven 60 forty-firsts of an inch from center to center, and the middle hole will be at an equal distance between the said upper and lower holes.

A glass spirit-level, *e*, is on the top surface 75 of the body and extends crosswise thereof, and is used simply when it is desired to level the instrument both ways. A glass spirit-level, *D*, is also on top of the body and extends lengthwise thereof. This glass is provided 80 with cross gage-marks *f* and two sets of numbers, as 1 2 3, are fixed on the plate, one number adjacent to each mark. The numbers commence at the center with 1, and from thence extend both ways. Each cross-mark is to designate the position of the air-bead in the glass tube, and this position indicates the proportionate rise or fall of the body A toward one 85 end of a line. The marks *f* on the spirit-glass serve to aid the workman in making the proper 90 grade between marked stakes on a line surveyed for a ditch or road-bed, as hereinafter described.

The extensible standard which is employed to support the level-body include the two upright bars *E E'*, which are connected by two encircling bands *h* in such manner that said bars may slide endwise on each other. One bar has a series of holes which are spaced apart at certain distances. In Fig. 1 the holes are 95 designated by broken lines *i*. The other bar has a hole, *i'*, and carries a spring-finger, *i'*,

whose end works loosely through the said hole, and the end of this spring-finger is thus in position to enter any one of the series of holes *i* in the other bar, and thereby the spring-finger holds or serves to lock the two bars together 5 at any position to which they may be extended. When these two upright bars are adjusted to make the standard short, the instrument is in compact shape and may be more readily 10 packed or carried. The height of the standard also may be lessened when in use—as, for instance, in case of an overhead obstruction being in the line of "sight" between the instrument and the target. The bar *E'* has at its 15 lower extremity a metal point, *k*, a horizontal foot-piece, *l*, at one side, and a pointer, *l'*, at the opposite side. The foot-piece serves to depress the metal point into the ground, and the standard is designed to be set so that the 20 pointer *l'* shall have position exactly at the center of a predetermined mark (a cross-mark $\times$ for instance) on a stake, *l*, previously driven into the ground.

The pointer-bar *E'* is provided with figures 25 53 54 and so on, increasing upward on the bar. In adjusting the two bars the figure on the bar *E'* appearing just below the lower end of the bar *E* indicates the height in inches of the sight-line level above the $\times$ -mark on the stake. 30 The upper end of the bar *E* is provided with a double joint, *F* and *F'*, one entirely above the other, the one turning in a vertical plane at right angles to the other. Each joint has a segment-shaped plate, *m*, provided on its rim 35 with teeth *m'* and a screw or worm shaft, *n*, is mounted in bearings *o*, and has at one end a head or thumb-button, *n'*, by which it is turned. The worm-shaft engages with teeth on the segment-shaped plate. The segment-shaped plate 40 *m* of the lower joint, *F*, is provided on the side opposite its curved rim with an upward projecting bifurcated arm, *j*, and the segment-shaped plate of the upper joint, *F'*, is pivoted between the two branches of said bifurcated arm. The upper segment-shaped plate, *m*, 45 has a spindle or fixed prong, *p*, which occupies a hole in the under side and at the center of the level-body. By this construction the level-body is mounted on a swivel, and may 50 be turned in a horizontal plane, so as to point in any direction. It will thus be seen that by turning the thumb-buttons *n'* the joints may be operated and the body *A* leveled in cross-directions.

55 The target consists of a target-rod, *G*, and a sliding target-block, *H*. The rod is provided with figures designating feet, and these commence at the lower end with 1. The rod is sharp-pointed at the lower end to enter the 60 ground, and near the end is provided with a horizontal pointer, *q*, which is designed to have position at the $\times$ -mark on that stake, *l*, at which it may be set. The target side of the block *H* has a surface with several colors, so that it may be plainly seen, and on the back of the block is a central vertical groove, *r*, which is of breadth sufficient to pass

over the figures on the rod without rubbing them. The back also has guides', which keep it straight as it slides on the rod, and a clamping-spring, *r'*, by which it is retained on the rod wherever set. 70

A straight-edge drag-bar, *I*, may be made of wood or hollow steel, and has clamps or thumb-screws *s*. The level-body *A* may be removed 75 from the spindle *p* on the standard and set upon the drag-bar, to which latter it is attached by the clamping set-screws *s*. A draft-handle, *L*, is bifurcated at one end, to set astride of the level-body *A*, and a pin, *t*, passes 80 through the said bifurcations, and through a hole, *t'*, in the level-body, and thereby attaches the draft-handle. By thus mounting the level-body on a drag-bar of greater length and attaching the draft-handle, the level may be 85 drawn along the ground on the surface to be graded, and thus the incline of the ditch may be tested or properly arrived at by noting whether the air-bead of the spirit-tube has the position which it should have, as per the stake- 90 marks made by the surveyor. It is immaterial whether the handle *L* be attached to the level-body or to the drag-bar. Either will answer.

To use the instrument for estimating distances in laying off a line for a drain or road-bed where the total inclination or difference in altitude is known—if the cross-mark *f*, on the spirit-level *D*, be placed so that each one will represent a variation from the level of one inch per rod, and the operator looks through the "sights" at the target while one end of the air-bead is at a certain cross-mark, and then one end of the level-body is lifted until the air-bead moves to the next wire, and then move the target on the rod to bring it in sight again, each inch on the rod the target was moved from the first to the second position will represent a rod distant from the instrument or between the instrument and target. A stake, *l*, having a $\times$ -mark, having been set in the ground, the standard of the instrument is brought near the stake and set so that its pointer *l'* shall be at the center of the cross-mark on the stake. The body *A* should then be leveled by adjusting the thumb-buttons *n'*. The target *G H* should then be set up at the desired point, and the body *A* turned to proper position for viewing the target through the sights. After the line for a ditch or drain has been laid out and staked the workmen may grade a rod or two at random between two stakes on the line surveyed. By then placing the drag-bar, with the level-body on it, on the graded part the position of the air-bead will show whether the grade corresponds to that marked on the stakes. 115

Having described my invention, I claim and desire to secure by Letters Patent of the United States—

1. A level having its body *A* provided with a spirit-glass, and at each end a boss, *B C*, elevated above the top surface of the body, with a horizontal sight-bore, *a*, through each boss,

a plate, *c*, at the eye-boss bore having three sight-holes, *c'*, one above the other in a vertical line, and in the bore of the other boss a cross consisting of two wires at right angles with 5 each other, as set forth.

2. A level having, in combination, a body, *A*, provided with a spirit-level, a standard composed of two bars, *E E'*, side by side, which slide endwise on each other, and one of 10 said bars having a series of holes, *i*, and the other having a spring-finger, *i'*, which may enter any one of the said series of holes, as set forth.

3. A level having, in combination, a body, 15 *A*, provided with a spirit-level, a standard which supports the body and has at its lower extremity a point, *k*, and a horizontal foot-piece, *l*, at one side, and a pointer, *l'*, at the opposite side, as set forth.

20 4. A level having, in combination, a body, *A*, provided with two spirit-glass tubes, *e D*, which extend in directions crosswise of each other, a standard provided with two joints, *F F'*, one entirely above the other and each

25 turning in a vertical plane at right angles to the other, each of said joints having a segment-shaped plate, *m*, the curved rim of which

is provided with teeth, and a screw-shaft, *n*, engaged with the said teeth, as set forth.

5. A level having, in combination, a body, 30 *A*, provided with two spirit-glass tubes, *e D*, which extend in directions crosswise of each other, a standard provided with two joints, *F F'*, one entirely above the other, the lower one, *F*, having a segment-shaped plate, *m*, the 35 curved rim of which has teeth and is provided on the side opposite the curved rim with an upward-projecting bifurcated arm, *j*, and the upper one having a similar plate which is pivoted between the two branches of said bifurcated arm, as set forth.

6. A ditching-level having, in combination, a straight-edge drag-bar, *I*, a level-body, *A*, provided with a spirit-glass tube and mounted on the drag-bar, and a draft-handle, *L*, where- 45 by the drag-bar and level-body may be drawn along the ground, as set forth.

In testimony whereof I affix my signature in presence of two witnesses.

EDWARD REICHENBACH.
